UNITED STATES PATENT OFFICE.

LAZARD KAHN AND JACOB MARTIN, OF HAMILTON, OHIO, ASSIGNEES TO
F. & L. KAHN & BROS., OF SAME PLACE.

DESIGN FOR A PAN.

SPECIFICATION forming part of Design No. 25,132, dated February 4, 1896.

Application filed December 28, 1895. Serial No. 573,145. Term of patent 14 years.

To all whom it may concern:

Be it known that we, LAZARD KAHN and JACOB MARTIN, citizens of the United States, residing at Hamilton, Butler county, Ohio, have invented and produced a new and original Design for Pans, of which the following is a specification, reference being had to the accompanying drawing, which is a perspective view of a pan showing our design.

5 The leading feature of our design consists in a rectangular bottom margined on three sides by straight walls and on the remaining side by a wall straight at its base, where it joins the bottom and having a rim forming an arc of a circle, the width of the last-mentioned wall being greater at its center than at its ends where it joins the side walls.

15 A is the bottom of the pan, rectangular in form.

B is the front wall, which is straight. 20
C C are two side walls, which are also straight, an end of each joining an end of the wall B.

D is the rear wall, its extremity joining walls C, its base being straight and joining 25 the bottom A at E, and its rim forming an arc of a circle, wall D having a greater width at its center than at its ends where it joins the walls C.

What we claim is— 30
The design for a pan, as herein shown and described.

LAZARD KAHN.
JACOB MARTIN.
